UNITED STATES PATENT OFFICE

JOSEF MEISER, OF DORTMUND, GERMANY

CORRUGATED SHEET PILING

Application filed July 25, 1927, Serial No. 208,315, and in Germany June 28, 1926.

This invention relates to sheet piling sections for wall or coffer-dam constructions and aims to provide sections of improved inter-connecting form by which walls of increased strength or resistance moment may be produced.

The construction of metal walls by the use of inter-connecting sections of form producing a corrugated wall surface is well known and has certain recognized advantages. According to present constructions of such walls, the metal sections or sheets are usually lapped and/or connected together by means of rivets or bolts, but such inter-connections are both time-consuming and troublesome, while the completed walls have proven to have a relatively low resistance moment. As there have been very few practical developments in the art, these objections in the constructions of such walls have not been eliminated.

The present invention avoids these defects and enables a wall of any desired moment of resistance to be constructed in a very simple way without the employment of rivets or other auxiliaries. It embodies the use of inter-engaging or inter-connecting sheet pile members of shape permitting them easily to be rolled to any required dimensions and thickness. The desired result is achieved by disposing the joints to the outside and designing them in a way to correspond fully to the shape of the piling and to interlock completely. These joints are disposed preferably on the outer surface planes, i. e., at opposite sides of the neutral plane or axis of the wall, since this arrangement precludes any possibility of their springing out, but on the contrary tends to lock the joint more firmly against any forces that may be brought to bear thereon, so that perfect connection is obtained under all conditions.

Walls erected in accordance with this invention are particularly suitable for the construction of channels and the like.

The invention will be best understood upon further description with reference to the accompanying drawings wherein various embodiments thereof are illustrated.

In said drawings:

Fig. 1 is a fragmentary sectional representation of inter-connecting metallic wall sections embodying the invention;

Fig. 2 is a sectional representation of two sections connected in somewhat different relation;

Figs. 3 and 3^a illustrate the connection of sections according to a slight modification; and

Figs. 4 to 8 inclusive are fragmentary sectional representations of walls constructed from inter-connecting sections of slightly differing forms according to the principle embodying this invention.

Referring to the drawings, the metallic sections formed for inter-connection to build up a wall are of elongated S, V or U-shape (some being doubly or substantially doubly curved) whereby the completed wall will be of corrugation outline or form. It will be noted that regardless of the extent of intermediate curve or corrugation, the ends (i. e. end edges) of the sections are inter-connected in substantially the same way at opposite sides of the neutral plane or axis of the wall.

Fig. 1 illustrates the simplest type of joint satisfying the aforementioned requirements sufficiently for small loads or pressures. The ends (i. e. end edges) of the corrugated sections are so formed that a curved portion of one section may closely embrace or engage substantially around the correspondingly formed part at the end of an adjoining section. The extremital edge *a* at the curved end of one of the sections is bent inwardly and bears against an opposing shoulder *b* formed in the outer surface of the embraced adjoining section, while the extremital edge *c* of the latter bears against a shoulder *d* formed in the inner surface of the first or embracing section, thus providing a complementary joint or union between the sections which are uniformly alike.

If the corrugated wall constructed of sheet pile members or sections interlocked in the manner described is subjected to bending stresses, the extremital edge *a* of the one section will bear firmly against the shoulder *b* of the other, while the extremital edge *c* of

the latter will bear against the shoulder *d* of the first-mentioned section, in addition to which the curved end portions of the members or sections will be pressed tightly together so as practically to form an integral profile which will absorb the resistance.

Fig. 2 illustrates a similar joint or connection between two sections except that the opposing joint edges *e*:*f* and *g*:*h* of the respective members (corresponding with the edges *a*:*b* and *c*:*d* of these first described) are obliquely disposed so as to form a kind of wedge which makes shifting or slipping even more difficult.

This principle is further developed in Fig. 3 where the edge *l* of the embraced section has the form of a double wedge engaging in the recess *m* of the embracing section, while the opposing edges *i* and *k* of the sections have the simple wedge form shown in Fig. 2. However, said last mentioned edges may also be given a double wedge form as shown in Fig. 3^a.

Figs. 4 to 8 represent a series of slightly differing forms of sections designed for interconnection on the same principle. Fig. 4 illustrates sections of elongated S or semi-corrugation form (i. e. with a joint at each half curve or wave.) Figs. 5 and 6 illustrate several single corrugational forms of sections, and Figs. 7 and 8 illustrate multi-corrugational forms of sections, the joints in some instances being located alternately on opposite sides of the neutral plane of the wall (see Figs. 4 and 7) and in other instances on one side only of the neutral plane of the wall (see Figs. 5, 6 and 8).

The distance *H* between joints at opposite sides of the mesne line or axis of the wall or the width of the neutral plane thereof is made to depend on the desired resistance capacity of the wall (see Figs. 4 and 5).

In the drawings, the wall sections are shown as being of substantially uniform thickness throughout, but they may of course be dimensioned differently according to the varying load, as indicated in Fig. 1 wherein enlargement of the curved ends of the sections is represented by the dotted lines.

The angle of the joints or bends in the locking ends of the sections may be varied so as to produce flattened or more arched corrugational curves, and may also be made angular instead of rounded if desired.

Having now fully described my invention, what I claim as new and desire to secure by Letters Patent of the United States is:

1. Means for constructing corrugated metal walls, comprising correspondingly formed sheet piling sections inter-connectible end to end, said sections having oppositely but correspondingly curved end-portions adapting them to fit complementarily together with each partially embracing and partially embraced by another and with the

extremital edges of each engaging an integral inner and outer angular shouldered enlargement of its adjacent sections, whereby a close interlocking joint results between each of the sections.

2. Means for constructing corrugated metal walls, comprising correspondingly formed sections of sheet piling material inter-connectible end to end, said sections having correspondingly oppositely curved end-portions adapted to fit one another complementarily with each partially embracing another and with the extremital edges of each abutting integral shouldered enlargements in its adjacent sections, whereby an interlocking union results therebetween.

3. Means for constructing corrugated metal walls, comprising correspondingly formed curved sections of sheet piling material inter-connectible end to end, said sections having oppositely curved end-portions adapted to fit together complementarily with each partially embracing another with the extremital edge of its embracing portion shouldered and engaging a shouldered integral enlargement of one adjacent section and with the extremital edge of its embraced portion engaging a shouldered enlargement of its other adjacent section, whereby an interlocking union between overlapping sections results.

4. Sheet piling sections according to the first claim, wherein the extremital edge of each section partially embracing another is formed with a wedge-like integral enlargement engaging into a correspondingly grooved enlargement of the adjacent embraced section.

5. Sheet piling sections according to the first claim, wherein the extremital edge of each section partially embraced by another is formed with a wedge-like integral enlargement engaging into a correspondingly grooved enlargement of its adjacent embracing section.

6. Means for constructing corrugated metal walls, comprising correspondingly formed corrugationally curved sections of sheet piling material inter-connectible end to end, said sections having oppositely curved end-portions adapted to fit complementarily each with another in partial embracement, the extremital edges of each being adapted to engage integral shouldered enlargements of its adjacent sections to provide an interlocking joint therebetween.

7. A wall comprising a plurality of interlocking correspondingly formed sections of sheet piling material, said sections being formed with oppositely curved end-portions terminating in hook or wedge-like extremital edges and having integral shouldered enlargements near to and substantially parallel with their aforesaid extremital edges, said wedge-like edges and said shouldered en-

largements being adapted to receive related portions of embraced adjacent sections in an interlocking joint tending to bind more tightly when the wall is stressed.

5 In testimony whereof I have affixed my signature.

JOSEF MEISER.
